(57) **CLAIM**

The ornamental design for a square-edged cosmetic container with sliding mirror, as shown and described.

DESCRIPTION

FIG. 1 is a top perspective view showing my new design with its cover in a closed position and its sliding mirror in a concealed position;

FIG. 2 is a top perspective view showing my new design with the cover in its open position and the mirror in its exposed position;

FIG. 3 is a top plan view showing the cover in its closed position and the mirror in its concealed position;

FIG. 4 is a front end elevational view showing the cover in its closed position and the mirror in its concealed position;

FIG. 5 is a right side elevational view showing the cover in its closed position and the mirror in its concealed position;

FIG. 6 is a back end elevational view showing the cover in its closed position and the mirror in its concealed position;

FIG. 7 is a left side elevational view showing the cover in its closed position; and,

FIG. 8 is a bottom plan view showing the cover in its closed position and the mirror in its concealed position.

“The broken line showing of an applicator brush in FIG. 2 is for illustrative purposes only and forms no part of the claimed design.”
